LOCKSTITCH SHOE SEWING MACHINES

Harold Ernest Elliott and Stanley Ernest Frampton, Leicester, England, assignors to United Shoe Machinery Corporation, Flemington, N. J., a corporation of New Jersey

Application March 7, 1952, Serial No. 275,318

Claims priority, application Great Britain March 22, 1951

14 Claims. (Cl. 112—33)

The present invention relates to improvements in curved hook needle shoe outsole sewing machines in which there is a horizontal work support and a shuttle above the work support and more particularly to an improved loop taker and spreader arrangement for a sewing machine of the type disclosed in United States Letters Patent No. 2,056,670, granted October 6, 1936, upon application of J. Gouldbourn et al.

In the design of a curved hook needle lockstitch shoe sewing machine of the type indicated, it has long been recognized that for the best results in handling the threads going to make up a lockstitch seam, the use of a true shuttle which passes entirely through each loop of thread, has many advantages over the use of a loop taker type shuttle which merely carries each loop of thread about a thread supply case without itself passing through the loop. From a mechanical point of view however, the loop taker type of shuttle has advantages over the true shuttle particularly because a true shuttle requires a separate driver having a lost motion gap through which each loop of needle thread must pass as it is carried about the shuttle itself. This lost motion gap is not only a source of noise and undue wear on the shuttle driving connections when operated at high speeds but it also renders the problem of timing in the machine more difficult as a result of uncertainty in the position of the shuttle throughout the extent of the lost motion gap. Furthermore, a true shuttle requires a supporting raceway or bearing separate from the driver whereas the loop taker type of shuttle may be secured rigidly upon a shaft of sufficient length and diameter to insure proper rigid bearing support.

The design of the curved hook needle machine presents additional difficulties for the reason that each loop of thread carried through the work by the needle after being entered by a beak on the shuttle must be disengaged from the hook of the needle without subjecting the thread in the loop to the possibility of injury against the edges of the needle hook, the hook being of necessity formed with sharp edges overlying its thread carrying throat.

In both true shuttle and loop taker type shuttle machines where a design is intended for high speed operation, the best mechanical construction calls for a shuttle shaped in the form of a hollow cup with an internal raceway about its circumferential side walls in which a locking thread supply case is rotatably mounted, the thread case being retained against rotation with the shuttle to assist the separation of the sides of each needle loop as it is passed about the thread case. For this purpose the usual arrangement is to provide a discontinuous flange on the thread case surrounded by the raceway of the shuttle, one side of a loop of thread being engaged by one end of the flange on the thread case to prevent its rotation with the shuttle while the other side of the loop is carried by the shuttle about the thread case, imparting to the loop a 180° twist. An example of a shuttle with such thread case is disclosed in United States Letters Patent No. 2,208,999 granted July 23, 1940, upon application of W. T. Minett.

2

In the machine of the Minett patent a loop taker type shuttle is provided having an internally supported thread case in which the beak of the shuttle rotates in a plane extending entirely clear of the circular path defined by the curved hook needle. By mounting the shuttle and thread case in this manner, the lower edge of the shuttle is disposed as close as possible to the path of the needle so that a loop of thread may readily be transferred from the needle to the shuttle beak and, in being carried about the thread case, the loop of thread is drawn in a direction where it may readily be disengaged from the hook of the needle without danger of injuring the thread. By such arrangement, many other advantages also are obtained including elimination of lost motion gap in the driving connections for the shuttle, but, because it is essential to insure visibility and free space for manipulation of a shoe at the front of the machine, an elongated shaft supported by bearings for the shuttle is impossible and the shuttle of that patent accordingly is supported by a relatively thin guide plate fitting a narrow external raceway in the shuttle. Also the patented shuttle is driven by connections including bevel gear teeth formed on the shuttle itself and the angle between the thread extending from the point of needle operation to the shuttle with respect to the plane defined by the rotary path of the shuttle beak is such that special precautions must be taken to insure shedding of the loop from the shuttle beak after passing each needle loop about the thread case.

One of the various objects of the present invention is to provide an improved curved hook needle lockstitch sewing machine in which the benefits, from a standpoint of handling thread, of a true shuttle are obtained without the mechanical disadvantages necessitated by the use of a lost motion gap between the shuttle and its driving mechanism, the machine being capable of operating at speeds higher than those obtainable with a true shuttle machine without excessive noise or undue wear frequently occurring in a true shuttle type machine. Another object is to provide a machine of the type referred to with a loop taker type of shuttle in which the advantages of operation from a mechanical standpoint are greater than those found in the machine of the Minett patent. More specifically the purpose of the present invention is to provide an improved curved hook needle machine with a loop taker type shuttle and an internally supported thread case in which the shuttle is secured rigidly to an elongated rearwardly extending shaft provided with bearings of ample size for preventing undue wear when operated at high speeds.

50 The machine of the present invention includes generally the same elements employed in prior machines of the same type but, in accordance with the objects above noted, the shaft to which the shuttle is secured has aligned radial bearings, the axis of which is inclined at such an angle to the horizontal, and has a thrust bearing at such a lengthwise position that the plane defined by the shuttle intersects the circular path of the needle and, preferably, passes between the axis about which the needle oscillates and the point on the work at which the needle operates. 55 By locating the shuttle in a plane thus defined, no special precautions are required in effective shedding of each needle loop from the shuttle beak although the shuttle does act in carrying each needle loop about the enclosed thread case to draw the thread away from the hooked end of the needle in a manner which is detrimental to easy disengagement of the thread from the needle hook.

A further object of the invention is to provide means which will allow the use in a loop taker type of machine of a shuttle located above a horizontal work support and disposed in the position indicated, while at the same time, any inherent difficulties resulting from this shuttle location in disengaging the thread from the hook of the needle

are overcome. In carrying out this latter object, means separate from the shuttle is provided for lifting each loop of thread from the needle hook in a manner to avoid damaging the thread and to insure disengagement of the thread from the needle hook accurately at the proper time. In its illustrated form the loop retracting means consists of an arm cooperating with a loop spreader after the spreader has opened each needle loop for the reception of the loop taker. The loop retracting arm also assists in moving the thread in a spread loop toward the open throat of the loop taker after the loop is disengaged from the needle so that the loop will be amply spread for passage about the thread case. After the loop is disengaged from the needle the loop retracting arm is actuated in a reverse direction to avoid interference with the loop as it passes about the thread case and the retracting arm also is actuated transversely to the loop so that the loop is left free for movement about the locking thread supply case.

For retaining the thread case against rotation with the shuttle according to this feature of the invention, the rearwardly extending shuttle shaft is constructed in the form of a hollow tube through which passes a stationary shaft slidably supporting a thread case engaging member, all of the moving parts being located inside an oil retaining housing for the machine. Such construction results in extreme rigidity, great durability and freedom from vibration or erratic action under normal operating conditions. Also it is possible to clamp the retainer shaft where it projects from the tubular loop taker shaft. Preferably, the thread case engaging member consists of one of a pair of fingers slidably mounted in the stationary shaft and actuated alternately toward and from engagement with cooperating recesses in the locking thread case.

These and other features of the invention as herein-after described and claimed will more clearly be understood from the following description taken in connection with the accompanying drawings, in which:

Fig. 1 is a fragmentary perspective view of the upper portion of a shoe sewing machine head embodying the features of the present invention;

Fig. 2 is a view in left side elevation on an enlarged scale, partly in section and broken away of the shuttle, thread case and some associated parts of the machine;

Fig. 3 is a view in right side elevation of the loop spreader, the loop retracting arm, and the hook needle of the machine showing their relative positions after each loop has been drawn through the work by the needle;

Fig. 4 is a similar view of the same parts showing their positions after the loop spreader has acted and the loop taker beak, shown in dot-dash lines, has entered the loop;

Fig. 5 is a similar view of the same parts showing the position of the loop retracting arm while lifting the thread from the needle hook;

Fig. 6 is a similar view of the same parts after the needle loop has been disengaged from the loop spreader and the thread retracting arm;

Fig. 7 is a plan sectional view on an enlarged scale of parts contained in an oil retaining housing of the machine, certain parts having been broken away to illustrate more clearly the underlying construction;

Fig. 8 is a diagrammatic view of the path formed by the thread engaging end of the loop retracting arm as seen from above, the path of the needle being shown in broken line;

Fig. 9 is a view in right side elevation of the loop spreader and loop retracting arm together with their actuating mechanisms;

Fig. 10 is a plan view of a portion of the loop retracting arm actuating mechanism; and

Fig. 11 is a time chart showing the relative movements of the loop spreader, the loop retracting arm, and the locking thread case retaining members, plotted against rotation of the sewing shaft in degrees ending at the

stopped position of the shaft after the final stitch in a seam has been completed.

The illustrated machine is a shoe outsole stitching machine which, except as hereinafter described, is the same as that disclosed in the above-noted patent to Gouldbourn et al., to which reference may be had for a more complete understanding of the manner of construction and mode of operation. As in the machine of that patent the present machine makes use of a curved hook 10 needle 2 and a curved awl 4 which oscillate about a horizontal stud 6 having a fixed axis 8 in a circular path 9 (Figs. 3 to 6 inclusive), the needle and awl always remaining in the same fixed path. The work, indicated at 15 10, is secured in the machine during sewing operations by a feed clamp comprising a work support 12 having a horizontal work supporting surface 13 and a presser foot 14 which swing to and fro horizontally while gripping and feeding the work in a horizontal position past the point of operation of the needle and awl. The machine 20 also is provided with other stitch forming devices including a rotary take-up 16 (Fig. 1) which gives up and takes up thread operated upon during sewing. The work support and presser foot make their idle return movement along the line of work feed while the awl engages the work and holds it against backward movement with the work support and presser foot.

In the machine of the Gouldbourn et al. patent, the shuttle is mounted in a raceway above the work support for easy access and visibility and rotates only twice per 25 stitch forming cycle at an alternately accelerated and decelerated rate of speed. To rotate the shuttle of that machine it is engaged loosely by a driver. The Gouldbourn et al. shuttle also is of the type which passes through each loop of needle thread along with a thread case contained therein and is disposed with its loop entering beak rotating in a path defining a plane approximately intersecting the work at the point of needle and awl operation substantially perpendicular to the work so that after engaging each loop of needle thread with the 30 shuttle of the patented machine the loop is drawn away from the work in a perpendicular direction. Such arrangement of the shuttle is of advantage since it produces an elevating reaction on the work at right angles to the clamping surface of the presser foot so that the pull on the needle loop is adequately resisted by the presser foot. Also the loop passes bodily about the shuttle in the simplest possible manner between the loosely engaged shuttle and driver so that entanglement with other parts of the machine are avoided.

Unlike the machine of the Gouldbourn et al. patent, however, the present machine is provided with a rotary shuttle of the loop taker type secured rigidly to a supporting shaft making three complete rotations at uniform speed to each sewing cycle of the other stitch forming 35 devices in the machine;

With a shuttle of the loop taker type such as disclosed in the Minett patent in which each needle loop passes, only about the locking thread case contained in the shuttle, both sides of the needle loop extend from the open end of the shuttle at the rear thereof. In this latter machine, the beak of the shuttle rotates in a circular path defining a plane extending clear of the needle path and disposed in such position that the loop of needle thread as it is being carried about the thread case is forced to intersect the circular path of the needle, both sides of the loop lying along the same flat end wall of the thread case where its movements may be obstructed by other parts of the machine, such as the needle and needle guide. For this reason there is no natural tendency for the thread in the loop to clear the rearward end of the shuttle and accordingly, the shuttle of that patent is provided with a helical rib running from its open throat to its rearward end. During rotation of the shuttle after the loop is carried into its throat, the helical rib prevents the thread from being wound up with the shuttle, the

rib fending the thread rearwardly until it swings clear of the thread case end wall. This rib projects radially from the circumferential wall of the shuttle a substantial distance in a manner to require undesirable compromise in the motions of other parts of the machine, including those of the loop spreader.

The shuttle of the illustrated machine comprises a hollow cup-shaped assembly providing within it an enclosure for a supply of locking thread. Referring to Fig. 2 of the drawings, the shuttle is formed as an integral rigidly secured enlargement of a rearwardly inclined hollow shaft 18 journaled in a downwardly and forwardly extending sleeve 20 of a main oil retaining housing 22 which is fixed on the head casting in place of the cover referred to in the prior Gouldbourn et al. patent by the numeral 5. The shuttle also has formed thereon a loop-entering beak 24 (Figs. 4 and 5) and a counterbore along the internal surface of the enlargement. The counterbore together with an adjacent face of a retaining place 26 (Fig. 2) secured to the enlargement, provides a rectangular groove or raceway 28 in which is received a peripheral flange 30 formed on a locking thread supply case 32 of hollow cylindrical form closed at one end, which case is rotatably mounted inside the shuttle thereby.

The locking thread case has a central split sleeve 34 extending forwardly, on which a bobbin 36 turns freely, being retained thereon by a rim on the forward end of the sleeve. As with the peripheral flange on the locking thread case in the Minett patent, the present thread case is cut away leaving one end of the flange forming a thread guiding shoulder (not shown herein), and the thread case is restrained from rotation with the shuttle by retaining means arranged out of the area of operation occupied by the other stitch forming devices, as will be described hereinafter.

For rotating the shuttle, the hollow shaft 18 is driven by a gear 38 fixed to the rear end of the hollow shaft, which gear meshes at a ratio of 2 to 3 with a larger gear 40 fixed on a forward end of an intermediate shaft 42 journaled in bearings provided in the housing 22. The rearward end of the intermediate shaft carries a gear 44 which meshes at a ratio of 1 to 2 with a larger gear 46 fixed on a main vertical sewing shaft 48 which corresponds with and is driven in the same manner as the shaft referred to as 33 in the prior Gouldbourn et al. patent, at the rate of one revolution per cycle of the machine, all of the stitch forming devices including the needle being actuated by the main sewing shaft. The shuttle therefore, is constantly rotated at a speed of three revolutions per cycle of the stitch forming devices in the machine. It will be noted that as the shuttle is integrally connected to the hollow shaft 18 a loop of thread cannot be passed over the shuttle, but is passed only around the locking thread case with the sides of the loop both running across the forward end of the shuttle only.

The angle and lengthwise position of the shuttle shaft 18 are such that, with the shuttle rotating in a counter-clockwise direction as seen from the front of the machine, its front face and a plane defined by the rotary path of its beak, is inclined downwardly and forwardly toward the work 10, the plane of the shuttle beak being illustrated by the dot-dash lines of Figs. 4 and 5. When the needle has descended through the work and is withdrawn upwardly, a loop of thread, indicated at 49 in Fig. 5, is drawn through the work by the hook of the needle. A thread lifter, corresponding to the thread lifter referred to as 163 in the prior Gouldbourn et al. patent engages the right leg of the loop on the needle lifting it forwardly and upwardly, the thread being still retained in the hook of the needle, so that the shuttle beak during one of its rotations can enter the loop. The loop is then taken by the shuttle beak in its rotation and the portion of the loop which is on the inner side of the shuttle beak is caught by the thread guiding shoulder of the stationary locking

thread case. At about this point in the cycle, the thread leaves the needle hook. Continued rotation of the shuttle causes the inner left side of the thread loop caught by the locking thread case to be passed along the guiding shoulder behind the locking thread case while the outer right side of the thread loop passes across the front of the thread case, thus giving the loop a half twist in a clockwise direction as seen from above. As the rotation of the shuttle is completed the thread is shed from the thread case and the shuttle beam and is drawn downwardly clear of the shuttle by the take-up.

To restrain the locking thread case 32 from rotation with the shuttle, yet at the same time to allow the thread loop to pass behind it, the rear face of the locking thread case is provided with two notches 50 and 51 at substantially diametric points, which are engaged by two reciprocating locking thread case retaining fingers 52 and 54 slidingly mounted for axial movement toward and from the thread case. These fingers are of truncated V-shape in cross-section and are secured to the forward ends of two rods 56 and 58 which slide in two holes in a headed, stationary shaft 60. The shaft 60 extends along the inside of the hollow shaft 18 for the shuttle. The rear end of each rod is reduced in diameter forming a shoulder, against which shoulders abut springs 62 and 64 assembled on reduced ends of the rods.

To enable each needle loop to pass between the fingers 52 and 54 and the locking thread case, the rearward ends of the rods 56 and 58 pass loosely through a pair of blocks 66 and 68 held in engagement with the springs 62 and 64 on the rods by check nuts 70. Each block has formed upon it, a laterally projecting trunnion 72. The trunnions engage the forward end portions of links 74 and 76 as pivots, the rear ends of said links being 35 pivotally connected to depending arms of bell crank levers 78 and 80. The bell crank levers are pivoted on parallel shafts 82 and 84 mounted with their ends in a bracket 86 fixed in the housing 22 and in the housing itself. The other horizontal arms of the bell crank levers 78 and 80 carry cam follower rolls 88 and 90 which engage peripheral tracks in a cam 92, secured to the vertical sewing shaft 48. The cam tracks are so shaped and arranged that the fingers 52 and 54 are withdrawn alternately from engagement with the locking thread case to allow the passage of the needle thread loop behind the locking thread case, the first finger reengaging immediately after the loop has passed and before the second finger disengages in the manner indicated in Fig. 11. The shape of the fingers and character of resiliency provided by the springs 54 and 56 allow the fingers to become disengaged from the locking thread case in the event that the locking thread case becomes jammed in the shuttle, thus rendering breakage of machine parts unlikely.

The thread case retainer shaft 60 is secured in place at its upper end within a clamp 94 fixed to the housing 22. To steady the lower end of the shaft 60 it is loosely surrounded by a bushing 96 secured within the hollow shaft 18, the bushing rotating with the shaft 18.

The hollow shuttle shaft 18 is journaled in a complete and effective bearing system within the sleeve 20, which bearing system is of adequate size and durability for long continued service. The bearing system for this shaft comprises radial and thrust ball-bearings 98 and 100 for the upper end of the shaft and a radial bearing or bushing 102 in the sleeve at the lower end of the shaft 18. The radial bearings have their axis inclined upwardly from the horizontal to the rear of the machine for purposes to be set forth.

It will be appreciated that, since each stitch is formed during every third rotation of the shuttle, it is only necessary for the locking thread case retaining fingers to operate during that particular rotation, and that both fingers may be held in engagement with the locking thread case at all other times. This object is achieved by 70 actuating the fingers from the cam 92 on the vertical shaft

48 which rotates only once to every three rotations of the shuttle, and thus unnecessary movement and consequent wear of the fingers and locking thread case are obviated.

It will also be appreciated that the shuttle of the illustrative machine is integral with a relatively long rearwardly inclined shaft journalled in a complete bearing system and running at a constant relative speed as contrasted with the shuttle of the prior Gouldbourn et al. patent, the latter bearing system being of necessity incomplete to allow the passage of the needle thread loop toward and from the shuttle. The illustrated bearing system therefore is of definite advantage in reducing wear and maintenance costs, and in increasing the reliability in operation of the machine as well as improving lubrication of the parts.

For the purpose of spreading and holding open the loop of thread drawn up through the work by the needle 2 so that the shuttle beak may enter the loop, the illustrative machine is provided with a needle loop spreader or thread lifter 104 corresponding with the thread lifter referred to in the prior Gouldbourn et al. patent at 163 and actuated in substantially the same manner by means of a link 106, a lever 108 and a cam 110 (Fig. 9) fixed on the vertical shaft 48.

In the machine of the Gouldbourn et al. patent the shuttle is mounted to rotate on a horizontal axis with its loop entering beak rotating in a plane intersecting the point of needle operation on the work so that the shuttle beak engages each loop of needle thread and draws it substantially at right angles upwardly from the point of needle operation. The upward pull of the loop as it is drawn by the shuttle is resisted effectively by the clamping action of the presser foot on the work close to the point of needle operation. In drawing the loop upwardly the thread is readily retracted from the hook of the shuttle and from the loop spreader in a manner conducive to smooth thread handling.

With the loop taker type of shuttle provided in the present machine, in which the axis of the shuttle is inclined upwardly from the horizontal toward the rear of the machine, the plane of the shuttle beak 24 intersects the needle path between the point of needle operation and the needle axis. With this arrangement the shuttle beak after moving upwardly to enter a needle loop, moves forwardly, the front of the shuttle being inclined forwardly toward the work. While moving forwardly and upwardly as the beak enters the needle loop, the thread slides along the edge of the beak rearwardly in a manner more or less compensating for the forward component of beak movement so that the net result of the upward movement in the shuttle beak is to draw the needle loop at right angles to the work from the point of needle operation as in the Gouldbourn et al. machine. In addition to this advantage, the present shuttle having its forward end open and facing toward the point of needle operations instead of rearwardly away from it as in the machine of the Minett patent, affords a much smoother movement of the needle loop as it passes about the locking thread case. A particular benefit is obtained as the right or outer side of the needle loop is drawn upwardly by the shuttle. Instead of tending to wind about the shuttle as the shuttle rotates, as with the Minett shuttle, it is drawn at an angle to the plane of the shuttle so that it quickly passes across the front of the shuttle without the necessity of forming a thick radially projecting diagonal rib for this purpose as required by the Minett machine. Accordingly, the thickness of the circumferential shuttle side wall may be substantially reduced providing greater space for the other stitch forming devices about the sewing point.

The construction and arrangement of the loop taker type shuttle, thus set forth, retains all of the thread handling advantages of the true shuttle arrangement, disclosed in the Gouldbourn et al. patent. At high speeds the mechanical advantages of the loop taker type shut-

tle in the Minett patent are secured, but, without the disadvantages of the Minett shuttle, so far as requirements of exposed gear drive, relatively thin shuttle supporting raceway and radially projecting loop deflecting rib formation on the outer surface are concerned. The bushings for the present shuttle and thread case retaining members have readily accessible communicating passages to the oil retaining housing 22 for the machine, the inclination of the sleeve 20 in which the shaft rotates providing natural seepage of oil in the casing to all of the wearing parts without endangering overthrow on the work operated upon.

While avoiding a limiting requirement in the use of the Minett shuttle, the shuttle of the illustrated machine is somewhat at a disadvantage in disengaging the thread from the hook of the needle, and accordingly, additional loop retracting means is provided for this purpose. Without the retracting means, the needle thread would become stranded or injured on the barbed hook of the needle as the loop is drawn upwardly by the shuttle.

For the purpose of disengaging the thread from the hook of the needle 2 in a manner to prevent stranding, breaking or other injury to the thread, the illustrated machine is also provided with a loop retracting arm 112 (see Fig. 9) the loop engaging portion of which is of similar structure to the loop spreader 104, but which moves rearwardly in a substantially horizontal path into engagement with the thread along the length extending between the shuttle beak and the hook of the needle to lift the loop of thread out of the needle hook as the shuttle beak 24 raises the loop.

To actuate the loop retracting arm 112 it is formed, above its loop engaging end, with a hole 114 through which passes a pin 116 forming a pivot for its oscillation transversely toward and from the spread needle loop along the line of work feed. The pin 116 is secured to a swinging carrier 118 which in turn is pivoted for forward and rearward oscillation on coaxial pivots 120 carried by a bracket 122 attached to a forward extension of the housing 22. The swinging carrier 118 has formed thereon a rearwardly extending arm to which is pivotally connected at 124 one end of a link 126. The other end of the link 126 is pivotally connected to an upwardly extending arm of a bell crank lever 128 pivoted on a lateral fulcrum 130 supported in a portion of the housing 22, near the vertical cam shaft 48. A rearwardly extending arm of the bell crank lever 128 has a cam roll 132 engaging a cam track 134 in the cam 110. The connections described cause the loop retracting arm 112 to oscillate in a direction toward and from the needle.

In order to avoid unintentional engagement with the thread in the needle loop by the retracting arm 112 after the loop spreader 104 first engages the loop, the retracting arm is disposed slightly to the right of the needle when not performing its loop retracting operation, but moves transversely to the left across a plane passing through the circular path of the needle, just above the needle hook. To impart transverse movement to the loop retracting arm it extends upwardly beyond its pivot pin 116 and is constructed with a socket for one end of a ball ended link 135, the other end of which is similarly connected to an arm of a small bell crank lever 136 which is pivoted on a vertical fulcrum 138 projecting upwardly from the bracket 122. A laterally extending arm of the bell crank lever 136 is pivotally connected to one end of a horizontal link 140, the other end of which is pivoted to a cam lever 142 (Figs. 7 and 9). The cam lever 142 is fulcrumed on a vertical shaft 144 fixed in the housing 22. The cam lever 142 carries a roll 145 (Fig. 7) which rides in a track 146 formed in the upper face of the cam 110.

Referring to Fig. 11 the resultant movement of the thread retracting arm when the two motions just described are combined when seen from above is substantially trapezoidal in form as shown in Fig. 8. During

a portion of the time during which the loop of thread is being drawn up through the work by the needle, the spreader 104 is stationary behind the needle point and the loop retracting arm 112 is stationary above but slightly to the right of the loop so that the loop is not obstructed when lifted by the spreader as shown in Fig. 3. As the needle continues its upward movement along its arcuate path the loop is carried rearwardly and the spreader 104 commences to swing forwardly and upwardly taking with it the right side of the loop, looking from the front of the machine, to open the loop for the entry of the shuttle beak.

In Fig. 4 the beak is shown as it starts to lift the loop. The retracting arm 112 by this time has commenced to move rearwardly and to the left of the machine across the plane of the needle path, and continues in that direction until it engages the loop and lifts it clear of the hook of the needle, as shown in Fig. 5. The shuttle beak 24, in the meantime, is swinging upward, forwardly and to the left, a portion of the loop sliding along the beak into the throat of the shuttle. The retracting arm then moves forwardly with substantially no right transverse movement, giving up the thread only as the loop is taken up by the shuttle.

It will be appreciated that during the time the thread is engaged with the retracting arm 112, as shown in Fig. 5, it will be deflected less and less by the arm as the arm moves forwardly until the thread reaches a straightened position, at which time, the retracting arm becomes disengaged therefrom. It will also be appreciated that at that same instant the retracting arm becomes disengaged from the thread, there will be no "twanging" or snapping action of the thread laterally off the retracting arm. To assist in this purpose the return transverse movement of the retracting arm is delayed until it has moved sufficiently forwardly to become completely disengaged from the thread. As the needle loop reaches a position where it is free of the shuttle, the retracting arm returns to a left transverse position while completing its forward movement and commences its rearward movement, continuing it until the retracting arm returns to the position shown in Fig. 3. It will be recognized that the action of the loop retracting arm 112 in lifting the loop cleanly out of the needle hook is likely to reduce sliding, stranding or other injury to the thread on the sharpened edges of the needle barb.

The nature and scope of the invention having been indicated and a particular embodiment having been described, what is claimed is:

1. In a shoe sewing machine, a curved hook needle, a stud having a fixed axis about which the needle operates in a circular path, a hollow cup-shaped shuttle having a needle loop entering beak and an internal raceway, and a thread case rotatably mounted in the raceway, the combination with an elongated shaft to which the shuttle is rigidly secured and an oil retaining housing for the machine including a downwardly and forwardly inclined sleeve communicating with the housing, in which sleeve the shuttle shaft is rotatably mounted with its axis similarly inclined, the shaft being disposed in a lengthwise position where the plane defined by the shuttle beak intersects the circular path of the needle.

2. In a shoe sewing machine, a curved hook needle, a stud having a fixed axis about which the needle oscillates in a circular path, a hollow cup-shaped shuttle having a needle loop entering beak and an internal raceway, and a thread case rotatably mounted in the raceway, the combination with a shaft to which the shuttle is rigidly secured mounted to rotate in the machine at both an angle and a lengthwise position in which the plane defined by the shuttle beak intersects the circular path of the needle, and means passing lengthwise through the shuttle supporting shaft for retaining the thread case against rotation with the shuttle during sewing operations.

3. In a shoe sewing machine, a curved hook needle, a

stud having a fixed axis about which the needle oscillates in a circular path, a hollow cup-shaped shuttle having a needle loop entering beak and an internal raceway, and a thread case rotatably mounted in the raceway, the combination with a shaft to which the shuttle is rigidly secured mounted to rotate in the machine at both an angle and a lengthwise position in which the plane defined by the shuttle beak intersects the circular path of the needle, and means passing lengthwise through the shuttle supporting shaft for retaining the thread case against rotation with the shuttle during sewing operations and comprising a stationary shaft surrounded by the shuttle shaft and a thread case engaging member slidably mounted for axial movement toward and from the thread case within the stationary shaft.

4. In a shoe sewing machine, a curved hook needle, a stud having a fixed axis about which the needle operates in a circular path, a hollow cup-shaped shuttle having a needle loop entering beak and an internal raceway, and a thread case rotatably mounted in the raceway, the combination with an elongated shaft to which the shuttle is rigidly secured mounted for rotation on an axis extending downwardly and forwardly of the machine and disposed in a lengthwise position in which the plane defined by the shuttle beak intersects the circular path of the needle, and means separate from the shuttle and mounted for movement in proximity to the position of a loop of needle thread as it extends between the shuttle and the needle for lifting each loop of thread carried through the work from the hook of the needle.

5. In a shoe sewing machine a curved hook needle, a stud having a fixed axis about which the needle oscillates in a circular path, a hollow cup-shaped shuttle having an internal raceway, and a thread case rotatably mounted in the raceway, the combination with an elongated shaft to which the shuttle is rigidly secured, bearings for the shaft in which the shaft is rotatable about an axis extending downwardly and forwardly of the machine, a loop spreader for opening each loop of needle thread for entry of the shuttle and a loop retracting arm acting after the loop spreader has opened a needle loop for entry of the shuttle to engage the thread in the loop between the shuttle and the needle for lifting it from the needle hook.

6. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its peak intersects the circular path of the needle.

7. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle between the needle axis and the point of needle operation on the work,

the front of the shuttle being inclined forwardly toward the work.

8. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle, and means separate from the shuttle for lifting each loop of thread from the hook of the needle.

9. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle, and means separate from the shuttle for lifting each loop of thread from the hook of the needle, comprising a retracting arm mounted for movement in proximity to the position of a loop of needle thread as it extends between the shuttle and the needle for engaging the needle loop and lifting it from the hook of the needle.

10. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle, a loop spreader for opening each loop of needle thread for entry of the shuttle beak and a loop retracting arm mounted for movement in proximity to the loop of needle thread extending between the shuttle and the needle for engaging the loop and lifting it from the hook of the needle.

11. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft,

the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle, means separate from the shuttle for lifting each loop of thread carried through the work by the needle from its hook comprising a retracting arm mounted for movement in proximity to the loop of needle thread extending between the shuttle and the needle and a carrier on which the retracting arm is movable transversely from the needle loop.

12. In a shoe sewing machine, a main sewing shaft, a curved hook needle actuated by the main sewing shaft, a stud having a fixed axis about which the needle oscillates in a circular path, a hollow cup-shaped rotary shuttle having a loop entering beak and an internal raceway, a thread case rotatably mounted in the raceway, a clamp for securing the work in a substantially horizontal position during sewing operations, and a shaft to which the shuttle is rigidly secured driven from the sewing shaft, the combination with a bearing system for the shuttle shaft having alined radial bearings, the axis of which is inclined at an angle to the horizontal, and having a thrust bearing for retaining the shuttle in a position lengthwise of the shuttle shaft axis in which a plane defined by its beak intersects the circular path of the needle, and means separate from the shuttle for lifting each loop of thread carried through the work by the needle from its hook comprising a retracting arm mounted for movement in proximity to the loop of needle thread extending between the shuttle and the needle and a carrier on which the retracting arm is movable transversely from the needle loop, and mechanisms for actuating the retracting arm and carrier to move the arm transversely to a position within the loop of thread engaging the needle before moving it in a direction to lift the thread from the needle hook.

13. In a shoe sewing machine, a curved hook needle, a shuttle and a loop spreader for opening each loop of thread carried by the needle for entry of the shuttle, the combination with a loop retracting arm mounted for movement in proximity to the thread extending between the shuttle and the needle to lift the thread from the hook of the needle after the loop spreader has opened it.

14. In a shoe machine, a curved hook needle, a stud having a fixed axis about which the needle operates in a circular path, a hollow cup-shaped shuttle having a loop entering beak and an internal raceway, a thread case rotatably mounted in the raceway and a clamp for securing the work in a horizontal position during sewing operations, the combination with an elongated shaft to which the shuttle is rigidly secured mounted for rotation about an axis extending downwardly and forwardly of the machine and disposed in a lengthwise position in which a plane defined by the shuttle beak intersects the circular path of the needle.
